UNITED STATES PATENT OFFICE

2,351,497

MUSICAL INSTRUMENT

Basil N. Fomeen, Los Angeles, Calif.

Application April 15, 1941, Serial No. 388,687

2 Claims. (Cl. 84—170)

This invention relates generally to the art of the production of music, and more particularly to a novel musical instrument.

Among the objects of the present invention, lies the provision of a musical instrument which has means for the production of a plurality of musical sounds having different timbre, either singly or in various combinations for the purpose of obtaining new musical effects, or old musical effects in a more convenient and efficient manner.

In accordance with the herein described improvements introduced in the orchestral field, a large increase in the versatility of the orchestra has resulted. The result of this is that the ability of a limited number of players, operating in a congested space and with a limited number of separate instruments, to produce the musical effects ordinarily produced by more men with greater space and equipment is of tremendous value in the musical field. This value is both commercial and artistic. Artistic in that the tonal effects of a large organization employing greater space and instrumentation are produced; and commercial in that there is a saving in labor, space and capital investment.

A principal object of the present invention lies in the provision of a composite orchestral instrument which I have chosen to call "The Basifon Grand." This instrument combines in a single composite structure means for producing the musical sounds of the piano, organ, vibraphone, chimes and cymbalum.

Another object herein lies in the provision of an instrument capable of producing the above described musical sounds in which there is a desirable coaction between the playing keys, and the musical elements by means of electrical devices so that the response to the player's touch is practically instantaneous, yet an entirely natural and unmechanical effect is produced.

A feature of the present musical instrument is that a single player may operate a plurality of the musical effects at the same time or in quick succession, without undue loss of time between the different effects or undue effort on the part of the player even in long sequences.

A further feature of the present structure lies in the simplicity and durability thereof so that the same may be manufactured at relatively low cost, readily serviced, and easily maintained in perfect playing condition.

Instruments manufactured in accordance with the present disclosure satisfy the professional

player by means of their stability and maintenance of proper tonal quality.

As is well known to those skilled in the art of musical instrument design and fabrication, 5 musical sounds having the greatest fullness (overtone frequency and total frequency range) are produced in instruments having resonators, baffles and chambers of adequate size. Pursuant to my novel construction, proper resonators, baffles and chambers are provided for all 10 of the musical elements, but these are in such arrangement and organization that the instrument is desirably compact.

The present invention is an improvement over 15 the construction shown and described in my Patent No. 2,222,223 granted November 19, 1940.

The above objects and other incidental ends 20 and advantages will more fully appear in the progress of this disclosure and be pointed out in the appended claims.

In the drawings constituting a material part 25 hereof, similar reference characters designate corresponding parts throughout the several views, in which:

25 Figure 1 is a plan view of a first embodiment of the invention with the top cover removed. In this view, the chime solenoids and armatures, and the piano strings are not shown, for purposes of clarity.

30 Figure 1-a is an enlarged fragmentary vertical sectional view as seen from the plane 1-a on Figure 1, and shows the mode of suspension of the left ends of the chimes.

35 Figure 1-b is an enlarged fragmentary elevational view as might be seen generally from the plane 1-b on Figure 1 and shows the mode of suspension of the right ends of the chimes.

40 Figure 2 is a horizontal sectional view, with some of the parts broken away, as might be seen generally along the plane 2-2 on Figure 3.

Figure 3 is a vertical sectional view with some parts in elevation as might be seen generally along the plane 3-3 on Figure 1.

45 Figure 4 is a fragmentary enlarged detail view of a piano, hammer and cymbalum effect mechanism, as shown in Figure 3, the parts being in the retracted position thereof.

50 Figure 5 is a view similar to Figure 4 but shows the cymbalum effect mechanism in the active position thereof.

Figure 6 is a fragmentary enlarged plan view of the vibraphone.

55 Figure 7 is an enlarged fragmentary plan view of one of the electrical keyboards.

Figure 8 is a fragmentary vertical sectional view of one of the electrical keyboards as might be seen from the plane 8 on Figure 7.

Figure 9 is a fragmentary vertical sectional view, some parts being seen in elevation, as might be seen from the plane 9-9 of Figure 8.

Figure 10 is an enlarged fragmentary vertical sectional view, schematic in nature, as might be seen from the plane 10-10 on Figure 8.

Figure 11 is an electrical circuit diagram showing the hook-up of the chime and vibraphone keyboards and the chimes and vibraphone and other electrical components.

Figure 12 is a fragmentary horizontal sectional view as seen from the plane showing the organ mechanism.

Figure 13 is a fragmentary enlarged vertical sectional view as seen from the plane 13-13 on Figure 12.

Figure 14 is a fragmentary enlarged vertical sectional view as seen from the plane 14-14 on Figure 6.

Figure 15 is a front elevational view of the first embodiment of the invention as might be seen from the left of Figures 1 or 2.

Figure 16 is a fragmentary vertical sectional view of the organ suction box as seen from plane 16-16 on Figure 15.

Figure 17 is an enlarged fragmentary detailed sectional view as seen from the plane 17-17 on Figure 16.

Figure 18 is a view taken similarly to Figure 13, showing, however, another form of the organ valve operating connecting rods.

Figure 19 is a view taken similar to Figure 5, but shows the mandolin or cymbalum effect mechanism in its lowered or inactive position.

Figure 20 is a fragmentary plan view taken similarly to Figure 1, but shows an alternate form of chime damping mechanism.

Figure 21 is an enlarged fragmentary vertical detail sectional view as seen from the plane 21-21 on Figure 20.

Figure 22 is a fragmentary vertical sectional view, partly in elevation, showing the mandolin or cymbalum effect mechanism in active position on the second embodiment of the invention seen in Figure 23.

Figure 23 is a front elevational view of a second embodiment of the invention, the upper and lower front cover panels having been removed to expose parts to view.

Figure 24 is a plan view of vibraphone unit as removed from the lower portion of the main casting of the second embodiment.

Figure 25 is an enlarged fragmentary vertical sectional view as seen from the plane 25-25 on Figure 24.

Figure 26 is an enlarged fragmentary vertical sectional view as seen from the plane 26-26 on Figure 24.

Turning now to the first embodiment of the invention, illustrated in Figures 1 to 19 inclusive, the musical instrument is generally indicated by numeral 20 and comprises broadly a case 21, a piano 22, an organ 23, a vibraphone 24, chimes 25, and cymbalum effect mechanism 26.

The case 21 has the general size and configuration of grand piano cases presently used, and includes the top wall or cover 21; a curved rear wall 28; front walls 29, 30, 31 and 32; left side wall 33; right side wall 34; and bottom wall 35. The case is supported in a horizontal position above the floor 36 by means of a pair of front legs 37, only the left hand one of which

is seen in the drawings in Figure 3 and a rear leg 38. The cover 21 is preferably hingedly connected along the left hand edge thereof to the upper edge of the left side wall 33, so that the cover may be opened and retained in an angular open position by means of a pivoted brace as is well known in grand piano construction. When this cover 21 is open, it serves to reflect and thus project the sounds emanating from the case 21 and the organ case 39. Thus all of the music producing means in the instrument 20 are adapted and positioned to have the sound vibrations created thereby, cast and/or reflected by the case 20.

Disposed above the bottom wall 35, at the forward portion of the instrument 20 is a stationary base plate 45, best seen in Figure 3. The stationary base plate 45 has extending perpendicularly upward therefrom, a vertical frame plate 46. The upper portion of the frame plate 46 is associated with the bed plate, the forward portion of which is indicated by numeral 48 and the rear portion of which is indicated by numeral 47. The portion 48 includes vertical and horizontal portions, the latter serving to carry the pin plate 49, which is the usual construction carrying a plurality of pins, about which the forward ends of the strings are wound. The pitch of the strings is adjusted by rotating the pins with a wrench. The strings themselves are supported adjacent the outer or rear ends thereof upon bridges which are connected to the sounding board. Since the strings, and associated supporting structure, as well as the sounding board and bridges are of standard well known construction, the same are not particularly shown in the drawings, nor is a detailed description thereof considered necessary. In Figure 3, one of the strings is indicated by numeral 50.

Each of the music producing means is provided with its own manually operated keyboard, so that facing the musician at the upper front portion of the instrument 20 are the piano keyboard 51, the organ keyboard 52, the vibraphone keyboard 53, and the chime keyboard 54. The keyboards 51 to 54 inclusive are each independently operable, so that they may be played in sequence or at the same time, depending upon the dexterity or skill of the operator.

Disposed above the stationary base plate 45 is an auxiliary piano keyboard and action support plate 55. This plate may be detachably secured to the upper surface of the base plate 45 in any suitable manner as for example by screws (not shown). A longitudinally arranged bar (transversely of the instrument 20) carries thereon the plurality of fulcrums for the keys 57, the bar 56 being seen in Figure 3, guide means 58 being attached to the forward edge of the plate 55 to control the movement of the forward ends of the piano keys 57. In Figures 3, 4, 5, and 19, I have shown a conventional hammer action such as is used on the grand type of piano in which the strings are mounted horizontally, including the felt faced hammers 59 and felt faced dampers 60. The specific hammer action forms no part of the present invention and is therefore not described in detail. There are a plurality of the vertical frames 61 arranged in a row transversely of the instrument 20, as best seen in Figure 2, and the upper portions of the frames 61 not only support the fulcrums for the hammers 59 but also the cymbalum or mandolin effect mechanism frames 62. These frames 62 are

generally of H shape with the cross bar exaggerated in length, including the end bearing members 63 and the tie-bars 64. The forward ends of the end bearing members are provided with orificed ears which are pivotally connected to the blocks 65. The mechanism frames 62 are elevated or retracted by means of the bell crank structure 66. The bell crank structure 66 is provided with suitable bearings on the upper rear portions of the frames 61. The connecting rods 66 are connected to a suitable handle or lever adapted for manual operation, the lower portion of the rods 66 being broken off, and the handle or lever therefor not being shown in the drawings.

The purpose of the bell crank structure 66 and the pivotal mounting of the frames 62 is to permit the said frames and the other parts attached thereto to be lowered or retracted when the plate 55 is placed into position on the plate 45, and then after the plate 55 is in proper position, the frames 62 may be elevated. This construction permits use of applicant's cymbalum or mandolin effect producing mechanism in grand piano construction where there is relatively close spacing between the piano hammer action having the hammers 59, and the positioning of the strings 50. This feature is of importance because it is considered highly undesirable to raise the total height of the piano case 21 when the same has the cover 27 in the closed position thereof, and also because it permits the use of the applicant's mechanism 26 by installation thereof in pianos having generally standard construction.

Each of the end bearing members 63 is provided with upwardly extending bearing posts 68, and each of the posts is provided with three aligned orifices which serve as journals for the axles 69, 70 and 71 (see Figure 19). The uppermost axle 69 has pivotally mounted thereon a plurality of buzzer elements 72. The buzzer elements 72 are preferably substantially flat metal strips having knuckles 73 at the upper ends thereof and metallic enlargements 74 at the lower or free ends thereof. The enlargements 74 are preferably in the form of solid semi-cylinders, the flat side thereof disposed along the axis of the cylinder being attached to the outer or rear face of the elements 72. There are as many elements 72 as there are strings 50 or hammers 59. The radius of the arc through which the elements 72 are rotatable is such that in the elevated or active position of said elements, the metallic enlargement will be positioned between the head of the hammer 59 and the string which the hammer is adapted to strike.

The axle 70 carries a plurality of felt carrying elements 75. The elements 75 are pivotally connected at the upper ends thereof upon said axle 70. The lower ends of the elements 75 are provided with a plurality of small felt blocks 76. Any suitable material having the required sound or vibration absorbing, or non-transmitting, characteristics may be used. I have found felt to be most suitable for this purpose.

The axle 71 has a plurality of radially directed integral extensions. These radial arms 77 are connected together by crank bars 78. Thus, the axle 71, the radial arms 77 and the crank bars 78 form a crank shaft extending transversely of the instrument 20. Rotation of the axle 71 counterclockwise, as viewed in Figures 4, 5 and 19, will result in the elevation of the felt carrying elements 75, the felt blocks on which will elevate the buzzer elements 72, thus bringing the metallic

enlargements 74 into proper position. The means for rotating the axle 71 may be any preferable structure well known in the piano art, such as flexible piano wire enclosed in rigid tubing or a series of links or links and levers. Such means are not illustrated in the drawings for purposes of clarity, but such means are preferably motivated by foot pressure upon the pedal 79 (Figure 15).

- 10 From a perusal of Figures 4, 5 and 19, the installation and operation of the cymbalum or mandolin effect producing mechanism 26 will be readily understood. In Figure 4, the mechanism is shown in the collapsed position thereof, just
- 15 prior to insertion into the front portion of the instrument casing. In Figure 4, the connecting rod 67 is in the lowered or inactive position thereof. When the connecting rod 67 is elevated, the bell crank structure 66 raises the end bearing members 63 to the elevated or expanded position thereof shown in Figure 19. As stated above, the movement of the connecting rod 67 is made only at the time the hammer action unit is installed within the instrument 20, so that during normal
- 20 use the parts take the position shown in Figure 19, the connecting rod 67 being lowered only for purposes of the repair or the replacement of parts, at which time the hammer actions and associated parts may be conveniently moved from
- 25 the case 21. An any time during the use of the instrument that it is desired to produce a cymbalum or mandolin effect, pressure upon the pedal 79 is transmitted to the axle 71 by means not shown, so that the same is rotated in a counter-clockwise direction, thereby placing the metallic enlargements 74 in a position between the strings 50 and the heads of the hammers 59. Since the enlargements 74 are thus in contact with the strings 50, part of the vibration of each of the
- 30 strings previously struck is transferred to the enlargements producing vibrations therein and a sound effect similar to that produced by a mandolin or cymbalum.

Turning now to a description of the organ 23 of the instrument 20, the organ includes generally the organ case 39, the keyboard 52, the stop controls 115, the reed box 80 and the suction box 81.

The arm 23 is preferably of a flat compact construction, so that the same may be disposed below the stationary base plate 45. As best seen in Figure 13, a plurality of reeds 82 are disposed over ports 83, which are in turn closed by spring pressed valves 84. The valves 84 are actuated by the valve push rods 85, which extend upwardly through the box 80, and a supporting frame 86, and thence through suitably disposed orifices in the stationary base plate 45 and the supporting plate 55. As seen in Figure 3, the push rods 85 then pass either through orifices in the piano keys 57 or through grooves cut in the opposed lateral surfaces of said keys. The push rods 85 then continue upwardly through the plates 87 and 88 through suitably disposed orifices therein and are engaged by the lower surfaces of the organ keys 52. The organ keys 52 are mounted for a limited rotation about a horizontal axis in any well known manner, as for example, by means of a row of pins mounted upon the rear portion of the upper plate 87. The forward ends of the keys 52 may be provided with the usual guides for maintaining them in proper position.

Within the organ case 39, there is also disposed a set of bass reeds 89 which are coupled

in a well known manner by means of the coupling levers 90. The forward ends of the levers 90 are actuated by the coupler push rods 91 in the usual manner.

The organ stops are located in sets of four, disposed at opposite ends of the organ keyboard 52 and include the stop operating knobs 92 to 99 inclusive. The knob 92 operates the octave coupler (not shown). The remaining knobs are connected in the usual manner by means not shown, to the stop controllers 103 to 109 inclusive. The knob 93 controls the bass reeds while the knobs 94 to 98 inclusive, control the various reed voices. The knob 99 controls the vox humana 110. The vox humana 110 comprises a beater, including a pair of oppositely disposed blades 111 and 112. The beater 113 is mounted upon a shaft therefor 114, which is suitably journaled at the ends thereof. The right hand end of the shaft 114 is connected to a suction driven turbine or air wheel, generally indicated by numeral 116. Both the reed box 80 and the turbine 116 are pneumatically connected to the suction box 81.

The suction box 81 is provided with an external suction box casing 117, best seen in Figures 3 and 15.

Turning now to Figures 15 to 17 inclusive, the suction box 81 is preferably of rectangular shape, but may be of any desired configuration. The box 81 is provided with an entrance orifice 118 and an exit orifice 119. A centrifugal blower fan 120 is driven by an electric motor 121. The motor is carried by a motor support frame 122 which mounts the same so that the motor shaft is vertically disposed. The frame 122 may be of any desired shape and is mounted upon the inner surfaces of the box 81 in such a manner that the vibration of the motor is insulated from said box. One means of providing this insulation is by means of the felt blocks 123. The upper wall 124, which has the orifice 118, is provided on the lower surface thereof with a bell 125 which acts as a conduit for the air withdrawn from the organ. As seen on Figure 17, the air withdrawn from the organ by the suction produced by the fan 120, follows the paths indicated by the arrows thereon. The bottom wall 126, which has the exit orifice 119, is provided with a gate valve 127. The gate valve 127 has an angularly disposed front face which is adapted to coact with the valve seat 128, so that when the valve 127 is moved forwardly, it allows the air within the box 81 to go out downwardly to reach the atmosphere. The valve 127 is mounted upon a radial arm 129, which in turn, is mounted upon a vertically disposed shaft 130. The shaft 130 is mounted in the journals 131 and 132, which are, in turn, supported inwardly off the front wall 133 of the suction box casing 117. The upper end of the shaft 130 is connected to the knee control 134. The knee control 134 is maintained in the inner or closed position thereof by means of the contractile spring 135.

Since the centrifugal blower creates an outward air pressure of relatively low order, the movement by the player of the knee control 134 and hence the valve 127, provides a sensitive and highly effective control of organ volume or swell. The organ 23 is, in the ordinary playing of the instrument, so used only during a portion of the playing time. The organ blower motor 121 is connected to the source of electrical energy by means of the mercury switch 138, which is pivotally mounted on the inner surface of the front wall 133 and connected mechanically by the link

139 to the knee control 140. The knee control 140 is maintained in the normally inner (off) position thereof by the contractile spring 141. This structure is best seen in Figure 15.

Figure 18 is a view corresponding generally to Figure 13, but shows another form of the organ valve and coupler push rods. These rods, indicated in Figure 18 by numerals 85' and 91', are made of small diameter stiff wire, preferably $\frac{1}{16}$ inch in diameter. The lower ends of the rods 85' and 91' are engaged by sockets 143 and 144 respectively, while the upper ends of said rods threadedly engage the heads 145 and 146. The decreased thickness of the rods permits them to pass more easily between the piano keys 51 while rotation of the heads 145 and 146 provides a simple adjustment of the effective length of said rods.

Turning now to a description of the vibraphone 24, best seen in Figures 2, 3, 6 and 14, this includes a plurality of vibraphone bells or bars 150, resonators 151, electrically operated hammers 152, rotating vanes 153, and a vane rotating electric motor 154.

The vibraphone chassis includes a central longitudinally disposed frame element 155, main plates 156 and 157 which are supported by the case 21 by means of the horizontally disposed posts 158, 159, 160 and 161.

The bars 150 are maintained in position by the cords 162 which are carried by channels 163 in turn attached to the plates 156 and 157. The resonators 151 are carried by the plates 156 and 157 in any suitable manner, and the longer resonators are of right angle elbow construction so as to avoid unnecessary height.

Disposed within the lower portions of the resonators are the vanes 153 which are mounted on shafts 164 and 165. The shafts 164 and 165 are suitably journaled at the front ends thereof, and forwardly of the rear ends which are provided with pulleys 166 and 167. The pulleys 166 and 167 are connected by means of the belts 168 and 169 to the motor pulley 170. In order to maintain uniform speed of rotation of the vanes 153, the motor 154 is provided with a governor 171.

The motor 154 need only run while the vibraphone is being played and so it may be started and stopped by means of a switch 172 which is located in a position convenient for the player (see Figure 15).

The tone bars 150 are maintained in a normally damped condition by means of the vibraphone damper generally indicated by numeral 173. The vibraphone damper 173 comprises a pair of spaced and parallel, horizontally and longitudinally disposed elongated members 174 and 175, which are interconnected by the transverse members 176, 177 and 178. Each of the members 174 and 175 is provided with a plurality of felt damper pieces 179 which engage the rear faces of the bars 150 being held in resilient contact therewith by the contractile spring 180. The spring 180 is connected at the rear end thereof with the element 177 and at the forward end thereof to the under surface of the frame element 155. Any suitable means such as piano wire in stiff tubing, or a series of links and levers (not shown) interconnect the damper 173 to the pedal 181 so that pressure on the pedal 181 results in the pulling of the damper felt pieces 179 out of contact with the tone bars 150. The disengaging movement of

the damper 173 is horizontally rearward of the instrument 20.

Each of the tone bars 150 has its own individual electromagnetically operated hammer 152. When the solenoids 182 are energized, as will be more particularly described hereinbelow, the plungers 183 rise to strike the undersurfaces of the tone bars 150. The hammers 152 are suitably mounted on longitudinally disposed channels 184 and 185, which are in turn supported by the bottom wall 35 in any suitable manner, as best seen in Figure 3, the bottom wall 35 having a cut out portion in which the hammers 152 are disposed.

The chimes 25 are best seen in Figures 1, 1a, 1b, and 3. The chime tubes 188 are horizontally disposed transversely of the instrument 20 and are positioned directly below the top wall or cover 27. The left hand ends of each of the chime tubes is provided with a pair of orifices diametrically oppositely disposed through which is passed a catgut string 189. At the beginning and end of the series, and between each of the chime tubes in the series, the catgut string is interlaced through a row of apertures 190 in a right angled frame member 191. The frame member 191 is attached to the inner surface of the left side wall 33, and is preferably spaced therefrom by the use of felt washers 192.

The chime tubes 188 are rung by a row of electrically operated hammers 193 including plungers 194 and solenoids 195. The hammers 193 are mounted upon the portion of the frame member 191.

The right hand ends of the chime tubes 188 are each suspended upon rubber bands 196 which extend between opposite pairs of posts 197 and 198. The pairs of posts 197 and 198 project vertically upward and are arranged in a stepped row along the support 199 therefor. Since the vibration of each of the chime tubes 188 is initiated at the left end thereof (the top of Figure 1) the support of the right end is very important so that the tone of the chime is not impaired. By the suspension of each of the right hand ends of the tubes at a point located inwardly from the right hand terminal thereof upon the catenary of a rubber band rigidly positioned at its ends, I have obtained a good chime tone without requiring the space needed when the chime tubes are suspended vertically in the usual manner.

The chime damper 200 comprises an axle 201 which is suitably journaled for rotation about a horizontal axis, the said journals as seen in Figure 1 being mounted on the inner vertical surface of the support 199. A plurality of radial fingers 202 all in the same plane carry at the ends thereof along rigid felt covered damper strip 203 adapted to engage the under surfaces of the tubes 188 when in the normally raised or damping position thereof. The front end of the axle 201 has a radial arm 204 which is pivotally connected to a push bar 205. The bar 205 is connected by suitable linkage (not shown) to the pedal 181 so that the chime damper 200 operates in unison with the vibraphone damper 173.

While as shown on the schematic electrical diagram on Figure 11, the circuits are marked positive and negative, this is for purposes of clarity only and the instrument operates equally well on direct or alternating current. The switch 206 connects the power source to a step down transformer 207 since the solenoids give most satisfactory operation at 16 to 25 volts. Obviously when direct current is available the trans-

former 207 may be substituted resistor of proper value.

The vibraphone keyboard 53 and the chime keyboard 54 are constructed in the form of a single unit which may be quickly and conveniently removed or replaced in the instrument 20. This combination keyboard unit generally indicated by numeral 209 is best seen in Figures 3, 7, 8, 9, 10 and 11 of the accompanying drawings.

The unit 209 includes a base plate 210 which has the front wall 30 attached to the forward edge thereof. The rear edge of the base plate 210 is provided a recess 211 while the rearmost edge portions of the base plate 210 are connected to the movable contact rail 212. The lower surface of the plate 210 carries the contact strip 213.

The forward lower surface of the bedplate portion 48 has affixed thereto a stationary contact rail 214.

Since both the electrical keyboards (53 and 54) have keys which are substantially identical, a detailed description of one will suffice for all. As best seen in Figures 3 to 10 inclusive the key 215 is composed of insulating material. Because of the voltages used dry wood is satisfactory. The lower surface of the key 215 is provided with a small saddle 216, U shaped in cross section and adapted to straddle a spring wire finger 217.

The contact finger 217 is of L shape the lower portion thereof being anchored in the base plate 210 and making electrical connection with the contact strip 213. The normal position of the finger 217 is seen in full lines in Figures 8 to 10 inclusive.

The rear ends of the keys 215 are pivotally mounted for rotation about a horizontal axis by means of the axle 218 which is journaled on the contact rail 212. The front face of the rail 212 is provided with a plurality of angularly disposed composite contacts 219.

The contact 219 is a small right angled piece of conducting material having a top portion 221 and a rear portion 220. The under surface of the top portion 221 is provided with a layer of insulating material 222. The vertical or rear portion 220 is provided with an orifice through which a screw 223 is passed which serves to attach the contact 219 to the rail 212. Each contact 219 has a connector 224 of substantially U shape the upper rear arm of which resiliently contacts a contact 225 on the rail 214.

The operation of the key 215 is as follows. When the key 215 is pushed downward by the player the finger 217 goes first into the position 226 on Figure 10. It then travels in the direction of the arrows on said figure returning to its original position by sliding against the layer of insulation 222. The parts are of such size and arrangement that only a short downward travel 60 of the key 215 will push the finger 217 to the position 227. From this position 227 the finger 217 springs back up to the position 228 (if the key 215 is kept in a depressed position), while if the key 215 has been released the finger will go back 65 to the starting or original position.

The principal advantage of the key structure 215 just described lies in the fact that by its use the solenoid 182 and 195 are only momentarily energized regardless of how long the key 215 is kept depressed on a single push by the player. This is of particular utility because it prevents the solenoids 182 and 195 from keeping the plungers 183 and 194 in contact with the vibraphone bars 150 and the chime tubes 188, after 70 they have started vibrating on a given stroke.

This is so because the solenoids while energized hold the plungers in the uppermost positions. This utility is of even greater value when the solenoids are energized by alternating current, because when this current is used, while the solenoids are actually energized any adjacent parts not absolutely solid and having magnetic properties will be caused to vibrate or buzz at the same pitch as the frequency of alternation of the electric current.

As seen on Figure 11 the high side of the line 230 is connected to one side of all of the solenoids 195 and 182. The returns 231 are connected to the contacts 225. From these contacts the circuit is completed via the connector 224, the contact 219, the spring finger 217, the contact strip 213 and thence via the conductor 232.

Directing attention now to Figures 20 and 21 there is seen an alternate form of the chime damping mechanism. Figure 20 is generally comparable to Figure 1 and for the purpose of avoiding needless repetition parts corresponding to those of Figure 1 are given singly primed reference characters. As previously described the chime damper in the alternate form generally indicated by numeral 200' is connected to and acts in unison with the vibraphone damper which as previously stated is controlled by the pedal 181. It may be mentioned here that the pedal 234 is the usual loud pedal for the piano 22 and controls the dampers 60 in the usual manner.

The principal difference between the alternate form of chime damper 200' and the chime damper 200, lies in the fact that in the former the damping is obtained by bringing felt covered damper discs 203' against the ends of the chime tubes 188'. I have found that in this manner I secure a more effective and satisfactory damping action. Furthermore since the pressure of the damper discs 203' is applied substantially longitudinally of the chime tubes 188' the constant raising and lowering of the chime tubes caused by the damper strip 203 is eliminated, with a consequent increase in the life of the rubber bands 196.

The damper discs 203' are normally maintained in the positions shown in Figures 20 and 21 and when the dampers are released or disengaged they are moved right or outwardly of the instrument 20.

Turning now to the second embodiment of the invention, there is shown in Figures 22 to 26 inclusive the manner in which the present invention may be adapted for use with a vertical or upright piano. Wherever possible for the purpose of avoiding unnecessary repetition, parts corresponding to those of the first embodiment are given doubly primed reference characters.

As seen in Figure 23 the vibraphone is mounted in the lower portion of the case 21'' and as contrasted with the first embodiment, the tone bars 150'' are arranged in a single row. The supporting frame 235 includes the longitudinal frame elements 236 and 237; the end frame elements 238 and 239; the plate 240; the frame members 241, 242, 243, 244 and 245, and the strips 246, which hold the frame member 245 in proper position. The resonators 151'' are maintained in position by the frame member 245. The lower surfaces of the frame members 243 and 244 are provided with felt padding 247 and the tone bars 150'' are supported therefrom in any well known manner. The solenoids 182'' are supported in a row upon the longitudinally disposed channel

248, which is supported at the ends thereof by means of brackets 249 (only the right hand one of which is seen in Figure 26).

The vibraphone damper 173'' is normally maintained in resilient contact with the lower surfaces of the tone bars 150'' by springs not shown, the damper 173'' being supported by means of the lever structure 250. The damper 173'' is, of course, connected by means not shown to the foot pedal 181''. In all other respects, the vibraphone 24'' operates in the same manner as in the first embodiment. By reason of the arrangement of the tone bars 150'' in a single row, all of the vanes 153'' may be mounted upon a single vane shaft, which is rotated through a gear reduction box 251.

The chime tubes, not shown, are suspended along the rear of the case 21''', while they are struck by the row of electrical hammers 193'' disposed above the top wall 27'', as best seen in Figure 2. Since the hammers 193'' operate by moving along a horizontal plane, they are preferably of the type in which the solenoid plunger is maintained in the inactive position thereof by resilient means.

The mandolin or cymbalum effect producing mechanism 26'' comprises a horizontally disposed bar 253 on which are mounted a plurality of buzzer elements 72'' in the form of right angled thin metal pieces. The upper ends of the buzzer elements 72'' are attached to the bar 253 in any suitable manner, while the lower rear surface of the buzzer elements 72'' is provided with metallic enlargements 74''. These enlargements 74'' are adapted to be positioned between the hammers 59'' and the strings 50'' when the bar 253 is lowered. The lowering of the bar 253 is accomplished by means of the bell crank structures 254 and 255, which in turn, are actuated by the pull rods 256 and 257, the lower ends of each of which are connected by means of a tie bar 258 to the pedal 79''.

It will be understood that since the springs 135'' and 141'' operate in a direction different from the springs 135 and 141, the knee controls (not shown) corresponding to the knee controls 134 and 140 are movable in the same directions nevertheless, so as to operate in the same manner as the knee controls 134 and 140, by reason of the fact that the said knee controls are associated with the shafts 130'' and 260 oppositely of the cranks 261 and 262, which, as viewed in Figure 23, are positioned rearwardly of the shafts 130'' and 260 respectively.

I wish it to be understood that I do not desire to be limited to the exact details of construction shown and described, for obvious modifications will occur to a person skilled in the art.

Having described my invention, what I claim and desire to secure by Letters Patent, is as follows:

1. In a musical instrument of the class described; a case having a stationary base plate; a plurality of piano strings vibratable at sonic frequencies and relatively stationary in position with relation to said base plate; a hammer action including a plurality of independently operable hammers and keys for actuating the same, said hammer action being detachably secured in position in spaced relation to said strings; means to provide cymbalum effect from the piano strings, including a movable buzzer element shiftable in position to a location between said hammers and said strings; said means being movable into first, second and third positions, said means in the first

position thereof being disposed at a distance from said strings at least equal to the distance between said hammers and said strings, said means in the second position thereof being disposed at a distance from said strings less than the distance between said hammers and said strings; and said means in the third position thereof having the buzzer element positioned between said hammers and said strings.

2. In a musical instrument of the class described; a case having a stationary base plate; a plurality of substantially horizontally disposed piano strings vibratable at sonic frequencies and relatively stationary in position with relation to said base plate; a hammer action including a plurality of independently operable hammers and keys for the actuating of the same, said hammer

action being detachably secured in position in spaced relation below said strings; means to provide a cymbalum effect from the piano strings including a movable buzzer element shiftable in position to a location between said hammers and said strings; said means being movable into first, second and third positions, said means in the first position thereof being disposed at a distance below said strings at least equal to the distance between said hammers and said strings, and in the second position thereof being disposed at a distance below said strings less than the distance between said hammers and said strings, and in the third position thereof having the buzzer element disposed between said hammers and said strings.
